Application April 29, 1948, Serial No. 146,042

Term of patent 14 years

(Cl. D48—2)

To all whom it may concern:

Be it known that I, Walter T. Heintze, a citizen of the United States of America, residing at Elizabeth, in the county of Union and State of New Jersey, have invented a new, original, and ornamental Design for Combined Candle Holder and Epergne, of which the following is a specification, reference being had to the accompanying drawing, forming a part thereof, wherein:

Fig. 1 is a top plan view of a combined candle holder and epergne, showing my new design.

Fig. 2, a vertical section, one of the candle holding elements and a portion of the center unit being illustrated in elevation; and,

Fig. 3, a bottom plan view of one of the candle holders.

I claim:

The ornamental design for a combined candle holder and epergne, as shown.

WALTER T. HEINTZE.
